DESIGN FOR A SCARF

Philip Goldenstein, New York, N. Y.

Application December 29, 1944, Serial No. 117,149

Term of patent 7 years

(Cl. D3—12)

To all whom it may concern:

Be it known that I, Philip Goldenstein, a citizen of the United States, residing at New York, in the county of New York and State of New York, have invented a new, original, and ornamental Design for a Scarf, of which the following is a specification, reference being had to the accompanying drawing, forming a part thereof.

In the drawing the figure is a face view of a portion of a scarf, showing my new design.

Approximately one-half of the scarf is shown. The full width of the scarf is disclosed horizontally and the design is repeated on the other half of the scarf in proper relation to complete the bordered scarf.

I claim:

The ornamental design for a scarf, as shown and described.

PHILIP GOLDENSTEIN.
